UNITED STATES PATENT OFFICE.

JOHN B. FOSTER, OF NEWARK, NEW JERSEY.

TOOTH-BRUSH HOLDER.

1,115,061.

Specification of Letters Patent. Patented Oct. 27, 1914.

Application filed May 13, 1914. Serial No. 838,251.

To all whom it may concern:

Be it known that I, JOHN B. FOSTER, a citizen of the United States, and a resident of Newark, in the county of Essex and State of New Jersey, have invented certain new and useful Improvements in Tooth-Brush Holders, of which the following is a specification.

The invention relates to a holder or receptacle for brushes having an extended handle and more particularly to that type of brush commonly known as a tooth-brush.

The present invention has for its object the provision of a receptacle that will incase the bristles or brush end of a tooth-brush so that the same may be kept clean and free from dust or other impurities which may be occasioned to contact or settle upon the brush.

20 A further object of the invention is to provide a sanitary casing for the bristles of the brush only, that may be used to advantage by travelers and may be conveniently carried in the pocket.

25 Other objects and features of the invention will appear as the specification proceeds.

In the accompanying drawings the invention is described in a concrete and preferred form but changes of construction may be made without departing from the legitimate and intended scope as expressed by the appended claims.

30 In the drawings: Figure 1 is a vertical side sectional view of the invention illustrating a brush placed therein. Fig. 2 is a vertical sectional view taken on the line 2—2 of Fig. 1 with the brush removed from the receptacle. Fig. 3 is a top plan view of the invention. Fig. 4 is a side elevation of the receptacle, and Fig. 5 is a horizontal view taken on the line 5—5 of Fig. 1 with the brush removed therefrom.

Similar characters referred to in the following specification denote similar and like parts throughout the several views of the drawing.

1 indicates a substantially tubular casing formed with, what may be termed, a flat back portion or wall 2. This casing is to be made preferably of an integral piece of material such as celluloid, although any other suitable material may be used. The back wall 2 has the lip or flange 3 formed thereon as a continuation of the upper end thereof, and is perforated, as at 4, so as to

engage with any suitable supporting member.

The lower end of the casing is partly closed by the bottom or restricting member 5 which is seated in a rabbet formed around the lower edge of the casing opposite said back wall and is cemented or otherwise suitably mounted therein. This member 5 is adapted to close only about one half of the opening in the lower end of the casing as to give sufficient clearance so the handle of the brush may pass therethrough but which will restrict the bristles of the brush from passing through the opening.

A closure 6 is pivotally mounted within the opposite or upper end of the casing by the pivot member 7 which has its opposite ends disposed in opposite sides of the casing at points adjacent said back wall 2. This pivot 7 is to be slightly spaced from said back wall and to extend parallel therewith. A lug 8 is formed on the closure 6 and projects rearwardly therefrom beyond its pivotal point and is to be of such a length as to engage with the back wall 2 when the closure is moved to a closing position; and when the same is seated or rests in the rabbet 9 formed in the upper edge of the casing so as to fully close the upper end thereof, the lug 8 will press upon the back wall 2 to deflect the same outwardly and, in view of its beveled face 8a, will be yieldingly held against accidental opening.

When the brush is applied in the casing 90 the back thereof is to lie flat against the back wall 2 and the handle thereof is to extend through the opening in the lower end of the casing, as is illustrated in Fig. 1. This casing 1 is to be only sufficiently large 95 to closely incase the brush end of the brush so that the bristles thereof will engage the front wall of the casing. By reason of the above-mentioned relation of the brush with the casing and the manner in which the closure 6 is mounted to the casing, namely, directly over the opening in the lower end thereof and spaced from the back wall 2, any upward movement tending to eject the brush through the entrance opening will 100 be prevented since the bristles of the brush hold the back thereof in close engagement with the back wall 2, and said upward movement of the brush would be restricted by the end thereof engaging with the lug 110 8 of the closure at the rear of the pivot 7, which thus only tends to force the closure

further in close position and to hold the tooth-brush within the casing. To remove the brush from the casing the closure 6 must be deliberately opened against the tension 5 of the back wall 2 upon the lug 8 and force must be exerted upon the handle of the brush to press the bristles thereof against the front wall of the casing so as to bend or deflect the same out of normal position so 10 that the end of the brush may be moved around the pivot of the closure 6 and thus out of the casing.

This invention is particularly designed for use in connection with tooth-brushes, 15 however, the construction thereof may be varied within the scope of the appended claims to be applicable to other brushes of a similar construction.

What is claimed, is:

- 20 1. A receptacle for tooth-brushes comprising: a casing constructed to snugly inclose the brush end of a tooth-brush, a bottom provided at the lower end of the casing and having an opening therein through which 25 the handle of the brush extends, means for closing the upper end of the casing; a pivot connection between said closing means and said casing and forward of the rear por-

tion of the casing so as to obstruct the opening in the upper end of the casing whereby 30 the bristles of the brush must be deflected from their normal position to draw the brush from the casing.

2. A receptacle for tooth-brushes comprising: a body member constructed to 35 snugly inclose the brush end of a tooth-brush and having a back portion against which the back of said brush will rest, a bottom member for the lower end of the body member to provide a rest for the bristles of the 40 brush and having an opening through which the handle of the brush will extend, a closure for the upper end of the body member having a portion hinged thereto forward of said back portion, a lug extending from the 45 closure and adapted to lie in the path of the back of the brush so that an upward movement of the tooth-brush will tend to close the closure.

Signed at Newark, in the county of Essex 50 and State of New Jersey, this 6th day of May A. D. 1914.

JOHN B. FOSTER.
